ADJUSTABLE LOCOMOTIVE SEAT

Hampton L. Hobby, Princeton, Ky.

Application May 28, 1937, Serial No. 145,372

3 Claims. (Cl. 155—88)

This invention relates to locomotive seats.

At the present time, as far as American railroads are concerned, the requirement is that locomotive seats be securely fastened to the floor of the locomotive cab at all times. Locomotive seats as now used and constructed are made of wood and are fastened to the floor of the cab in one position, without thought to the convenience of the engineer.

An object of the present invention is to provide a locomotive seat that may be adjusted to different positions and to different heights to suit the convenience of the individual engineer operating the locomotive, and which seat, at the same time, may be securely fastened to the floor of the cab to meet present railroad requirements.

The invention, together with its objects and advantages will be best understood from a study of the following description, taken in connection with the accompanying drawings, wherein:

Figure 1 is a top plan view of the seat with the upper section of the seat removed.

Figure 2 is a perspective view of the upper section of the seat.

Figure 3 is a vertical sectional view taken substantially on the line 3—3 of Figure 2, but with the upper section of the seat in an elevated position.

Figure 4 is a perspective view of a floor plate.

In accordance with the present invention there is provided a "dead" or stationary floor plate 5 provided with openings 6 to accommodate screws or other fastening elements 7, through the medium of which the plate 5 is secured to the floor 8 of the locomotive cab.

Resting on the floor plate 5 is the bottom 9 of the lower box-like section 10 of the seat. This section 10 in addition to the bottom 9 has side and end walls rising vertically from the bottom 9, and the section 10 is preferably formed wholly of metal.

Further, the seat comprises an upper section 11 which is of substantially rectangular frame-like form, constructed from sheet metal, and adapted to be lowered and telescoped into the lower section 10 of the seat.

To support the section 11 in either raised or lowered position with respect to the section 10, the latter is provided on opposed walls thereof with internal lugs 12 while the seat section 11 in each of two opposite sides thereof is provided with short notches 13, and in each of two other opposed sides thereof with longer notches 14.

As shown in Figure 3, to support the section 11

in elevated position relative to the section 10, lugs 12 are engaged in the shorter notches 13.

To support the section 11 in lowered and telescoped position relative to the section 10, lugs 12 are engaged in the longer notches 14, as is obvious.

The section 11 of the seat supports the upholstered seat 15 proper, and the same is hinged adjacent one edge thereof to one side of the section 11 through the medium of hinges 16 arranged within the confines of the section 11 and wholly concealed when the seat 15 is at rest on the upper edges of the section 11.

Except for the side thereof in which the seat 15 is hinged, the remaining sides of the section 11 at the upper edges thereof are bent outwardly to provide narrow flanges 17 upon which the seat 15, proper, rests when in the position shown in Figure 3.

Further, in accordance with the present invention, the floor plate 5 has rising therefrom and adjacent one corner thereof an integral stud bolt 18. To accommodate the bolt 18, the bottom 9 of the seat section 10 is provided with a slot arrangement shown in Figure 2 and which consists of a pair of right angularly related interconnected slots 19, 20, and a diagonal slot 21 that joins the slots 19, 20, at the angle between the slots 19, 20, as clearly shown in Figure 2.

To secure the seat at the desired position of adjustment relative to the floor plate 5, there is threadedly engaged with the stud bolt 18, a hand nut 22 adapted to be threaded home against a washer 23 disposed on the stud bolt 18 between the bottom 9 of the seat section 10 and the nut 22.

Obviously, provision of the intercommunicating slots 19 to 21 inclusive permits of a wide range of adjustment for the seat, permitting the latter to be moved laterally toward or away from the side of the locomotive cab or either backward or forward to suit the convenience of the engineer.

Manifestly, to adjust the seat to the position desired, the lever nut 22 is loosened and the seat is then slid in the desired direction, being guided to the position desired by means of the cooperating bolt 18 and slot section in the bottom plate of the seat structure. When the desired position is effected, the seat is securely fastened to the cab by tightening the lever nut 22.

The height of the seat may be readily raised or lowered simply by lifting out the section 11, giving it a quarter turn, and then placing it in the section 10 of the seat.

It will thus be seen that I have provided a locomotive cab seat which may, and is, in the preferred embodiment thereof, made of steel, and which is adjustable to any desired position to suit the convenience of the engineer operating the locomotive. Also, a seat embodying the features of the present invention will meet the requirements of the railroad, provision being made, as above noted, to securely fasten the seat to the floor of the cab, as is necessary to meet the present railroad requirements.

It is thought that a clear understanding of the construction, utility, and advantages of a seat of this character will be had without a more detailed description.

Having thus described the invention, what is claimed as new is:

1. In a locomotive cab seat, and in combination, a stationary floor plate having a bolt rising vertically therefrom, a lower supporting section having a bottom and vertical walls rising from said bottom, said bottom being provided with a plurality of angularly related intercommunicating slots to accommodate said bolt and to permit a shifting of the seat supporting section in substantially any and all directions relative to said floor plate, said seat supporting section having pairs of lugs on the inner side of two opposed walls thereof, a second seat supporting section telescoping within the first seat supporting section and provided on each of two sides thereof with elongated slots to engage said lugs, for supporting the second section in telescoped position within the first section, said second seat section having relatively shorter slots in each of two other opposed sides thereof for accommodating said lugs for supporting the second section in a raised position relative to the first section.

2. In a locomotive cab seat, and in combination, a stationary floor plate having a bolt rising vertically therefrom, a lower supporting section having a bottom and vertical walls rising from said bottom, said bottom being provided with a plurality of angularly related intercommunicating slots to accommodate said bolt and to permit a shifting of the seat supporting section in substantially any and all directions relative to said floor plate, said seat supporting section having pairs of lugs on the inner side of two opposed walls thereof, a second seat supporting section telescoping within the first seat supporting section and provided on each of two sides thereof with elongated slots to engage said lugs, for supporting the second section in telescoped position within the first section, said second seat section having relatively shorter slots in each of two other opposed sides thereof for accommodating said lugs for supporting the second section in a raised position relative to the first section, and a seat member hinged adjacent one edge thereof to one side of the second seat supporting section and resting on the top of said second section. 5 10 15

3. In a seat of the character described, a pair of telescoping hollow seat-supporting sections, the outer one of said sections having opposed sides provided with lugs on the inner faces thereof, and the inner one of said sections having two opposed sides thereof provided with elongated slots to engage said lugs for supporting said inner section at one position of adjustment relative to the outer section, and said inner section also having in two other opposed sides thereof relatively short slots for engagement with said lugs to support said inner section at a second position of adjustment relative to said outer section. 20 25 30 35
